UNITED STATES PATENT OFFICE

99,318

DESIGN FOR A COOKING RANGE

John A. Underwood, Evanston, Ill., assignor to
Montgomery Ward & Co., Incorporated, Chi-
cago, Ill., a corporation of Illinois

Application December 23, 1935, Serial No. 60,236

Term of patent 14 years

To all whom it may concern:

Be it known that I, John A. Underwood, a citizen of the United States, residing at Evanston, in the county of Cook and State of Illinois, have invented a new, original, and ornamental Design for a Cooking Range, of which the following is a specification; reference being had to the accompanying drawing, forming a part thereof.

In the drawing, the figure is a perspective view of a cooking range showing my new design, the side of the range other than that shown being substantially plain.

I claim:

The ornamental design for a cooking range, as shown and described.

JOHN A. UNDERWOOD.
